ATTORNEY

UNITED STATES PATENT OFFICE.

WILLIAM H. CUMMINGS, OF PHILADELPHIA, PENNSYLVANIA.

ENVELOP.

1,357,961.

Specification of Letters Patent.

Patented Nov. 9, 1920.

Application filed November 27, 1918. Serial No. 264,291.

To all whom it may concern:

Be it known that I, WILLIAM H. CUMMINGS, a citizen of the United States, and a resident of Philadelphia, in the county of Philadelphia and State of Pennsylvania, have invented an Improvement in Envelops, of which the following is a specification.

My invention relates to envelops which when closed have the appearance of being sealed but which are provided with means whereby access to the interior thereof is permitted in order that the contents may be examined if desired.

The advantage of such envelops is that they enable the distribution of certain matter in unsealed envelops or packages with the result that a saving in postage is effected.

One of the objects of my invention is to provide a construction of envelop in which the unsealed means for holding the circulars, papers or other contents therein and which is adapted to be opened to permit access to the interior thereof is securely retained in position, the retaining means, however, permitting ready and easy opening of the said unsealed means.

A further object of my invention is to simplify the construction thereby decreasing the cost of production of the envelops commercially, while at the same time increasing the strength of the envelop and also increasing the security of the holding means.

Other objects and advantages of my invention will be particularly pointed out in the detailed description thereof which follows or will be apparent from such description.

In order that my invention may be more readily understood and its advantages of construction more fully appreciated, reference may be had to the accompanying drawing in which I have illustrated one form of a convenient embodiment thereof. It will be understood, however, that changes in the details of construction may be made within the scope of the claims without departing from my invention.

In the drawing:—

Figure 1 is a plan view of the inner side of an envelop blank with the flap portions thereof ready to be folded to form my envelop;

Fig. 2 is a view with certain of the flaps folded into position leaving one of the flaps

ready to be folded into position over those previously folded;

Fig. 3 is a plan view of the bottom side of an envelop with certain of the flaps secured in closed position but with the flap for closing the upper side of the envelop in open position ready to be folded down;

Fig. 4 is a view of the bottom side of the envelop with the top closing flap in closed position and showing the unsealed flap removed from underneath the other flaps of the envelop;

Fig. 5 is a view similar to that shown in Fig. 2 but with certain of the adhesive material shown in Fig. 2 omitted;

Fig. 6 is a view of a portion of the flap shown at the right hand side of Figs. 2 and 5 with a further portion of the adhesive material omitted, and

Fig. 7 is a transverse sectional view taken on the line 7—7 of Fig. 4 but with the unsealed flap shown in closed position in full lines and in open position in dash and dot lines.

Referring to the drawing:—1 designates a portion of a blank which, when the envelop is constructed therefrom, constitutes the front side of the same. 2 designates a flap constituting an extension of one end of the portion 1, which flap is adapted to be folded inwardly upon the inner side of said portion and its lower edge, in the construction shown, is adjacent and is in parallel relation to the lower edge of the portion 1, as shown in Figs. 2 and 3 of the drawing. The flap 2 is provided with a slit 3 adapted to receive a flap 4, as clearly indicated in Figs. 2 and 5. The slit is situated at the lower side of the flap 2 and extends from the lower edge thereof, as shown. The lower portion of the flap 2 to the right of the slit 3, after the said flap has been folded over as shown in Figs. 2 and 5 of the drawing, is situated underneath or underlies the flap 4, while the portion thereof to the left of said slit, after it has been folded over, overlies the said flap 4 when the latter has been folded inwardly as shown in Figs. 2, 5 and 7. After the flap 2 has been folded inwardly as shown in Figs. 2 and 5, the flap 5 is then folded inwardly and is fastened to the flap 2 by means of the adhesive indicated at 6. In the construction shown, the lower edge of the flap 5 is adjacent and in parallel relation to the lower edge of the portion 1 and

110

is substantially of the same length as said portion. It will be noted that the said adhesive consists of a relatively narrow, elongated portion 6^a and a triangular portion 6^b. The latter portion is adapted to secure the end portion of the flap 5 to the portion 7 of the flap 2 intermediate the slit 3 and the portion 1 of the blank or the envelop.

It will be observed that the flap 5 is securely fastened to the flap 2 not only along the surface thereof which corresponds to the relatively narrow portion 6^a of the adhesive, but also along the relatively wide portion thereof corresponding to the triangular portion 6^b of the said adhesive material. It will be also observed that the bottom flap 4 may be readily removed from between the flaps 2 and 5, and from underneath the portion 7 of the flap 2, so as to open the bottom edge of the envelop and permit access to the interior thereof, as is clearly shown in Fig. 4 in full lines and by dotted lines in Fig. 7.

It will also be observed that by securing the flaps 2 and 5 together throughout a large proportion of their length, as indicated in Fig. 2, there are no loose edges upon either of the said flaps to catch the papers or other materials which may be inserted in the said envelop to interfere with their ready insertion. It will be understood, however, that the relatively narrow portion 6^a of adhesive may extend even farther along the flap 5 than is shown in Figs. 1 and 2 of the drawing; also that it may be shortened or omitted entirely, as is indicated in Figs. 5 and 6 of the drawing. In Fig. 5 only that part of the relatively narrow portion 6^a of the adhesive is retained which is parallel to the upper inclined edge of the flap 5, while in Fig. 6 the relatively narrow portion 6^a is entirely removed, leaving only the triangular portion 6^b which is adapted to be secured to the portion 7 of the flap 2 to the left of the slit 3 after the said flap 2 has been folded over upon the part 1, as shown in Figs. 2 and 5.

The top of the envelop is adapted to be closed by the closing flap 10 provided with adhesive material 11 upon its inner surface adjacent its outer edge by means of which said flap is adapted to be secured to the upper edge portions of the flaps 2 and 5.

It will be seen that I have provided a construction of envelop which, when the flap 4 is folded inwardly as indicated in full lines in Fig. 7 and when the flap 10 is in closed position also as shown in said Fig. 7, has the neat appearance of a sealed envelop. The postal authorities, however, have ready and convenient access to the interior of said envelop merely by removing the flap 4 from underneath the flaps 2 and 5.

It is apparent that by interlocking the flap 4 with the lower part of the flap 2 near

its point of attachment to the part 1, with a part of the flap 4 underneath a part of the flap 2 and with another part of the flap 4 above a portion or part of the flap 2, and with the last mentioned part of the flap 4 situated intermediate the flaps 2 and 5, I have provided an envelop in which the unsealed means for retaining the contents within the envelop is securely held or retained in closed position to prevent accidental loss of said contents.

The manner in which the bottom flap 4 retains the contents of the envelop therein and prevents the escape of the same therefrom is shown clearly in Fig. 7 in which the lower edge of the sheet of paper or other material 12 is shown seated in the fold between the said flap and the front side of the envelop.

I claim:—

1. An envelop comprising front and back sides, the latter consisting of overlapped end flaps which are secured together, the underneath one of said flaps having a slit extending from the lower edge upwardly therein, a bottom flap which is adapted to enter the said slit, one portion of said bottom flap when engaged with said slit being situated underneath a portion of the underneath end flap and the remaining portion thereof being situated between the said overlapping end flaps, and a top flap for closing the opening at the top edge of the said envelop.

2. An envelop comprising front and back sides, the latter including end flaps, one of which overlies the other, a slit extending from the lower edge upwardly in the underneath flap, said slit being situated relatively near the base end of said flap, means for securing the outer end portion of the overlying flap to the portion of the underneath flap which is situated between the slit therein and the adjacent base end thereof, a relatively narrow bottom flap which is adapted to extend into the said slit, one end portion of said bottom flap being situated between the front side of the said envelop and the said underneath end flap, and the other portion of said bottom flap being situated between portions of the said end flaps, and a top flap adapted to be folded over and secured to the upper edge portions of said end flaps for closing the top opening of said envelop.

3. An envelop comprising end flaps overlapped and constituting a part of the back side of the envelop, the underneath flap being provided with a slit extending upwardly from its edge, and a bottom flap adapted to extend into and through said slit whereby one portion thereof is situated underneath a portion of said flap and the remaining portion thereof above the said flap, and the portion of the underneath flap overlying

the bottom flap being secured to the top overlapping end flap.

4. An envelop comprising end flaps overlapped and constituting a part of the back side of the envelop, the lower edges of said flaps lying adjacent and in substantial parallel relation to the lower edge of the front side of the envelop, the underneath flap being provided with a slit extending upwardly 10 from its lower edge at a point adjacent the base end portion thereof, and a bottom flap adapted to extend into and through said slit whereby one portion thereof is situated un-

derneath the portion of said flap between said slit and the base end thereof, and the remaining portion thereof above a portion of said flap to the right of said slit, and the said overlying end flaps being secured together within the region between said slit and the base end of the underlying end flap. 15

In testimony that I claim the foregoing as my invention, I have hereunto set my hand this 26th day of November, A. D., 1918. 20

WILLIAM H. CUMMINGS.
